(57) **CLAIM**

We claim, the ornamental design for a rising arch luminaire arm, as shown and described.

DESCRIPTION

FIG. 1 is a perspective view of a first embodiment of a rising arch luminaire arm, showing the new design;

FIG. 2 is a side elevational view of the first embodiment;

FIG. 3 is a front elevational view of the first embodiment;

FIG. 4 is a top view of the first embodiment;

FIG. 5 is a perspective view of a second embodiment of a rising arch luminaire arm, showing the new design;

FIG. 6 is a side elevational view of the second embodiment;

FIG. 7 is a front elevational view of the second embodiment;

FIG. 8 is a top view of the second embodiment;

FIG. 9 is a perspective view of a third embodiment of a rising arch luminaire arm, showing the new design;

FIG. 10 is a side elevational view of the third embodiment;

FIG. 11 is a front elevational view of the third embodiment;

FIG. 12 is a top view of the third embodiment.

FIG. 13 is a perspective view of a fourth embodiment of a rising arch luminaire arm, showing the new design;

FIG. 14 is a side elevational view of the fourth embodiment;

FIG. 15 is a front elevational view of the fourth embodiment;

FIG. 16 is a top view of the fourth embodiment;

FIG. 17 is a perspective view of a fifth embodiment of a rising arch luminaire arm, showing the new design;

FIG. 18 is a side elevational view of the fifth embodiment;

FIG. 19 is a front elevational view of the fifth embodiment;

FIG. 20 is a top view of the fifth embodiment

FIG. 21 is a perspective view of a sixth embodiment of a rising arch luminaire arm, showing the new design;

(Continued)

FIG. 22 is a side elevational view of the sixth embodiment; FIG. 23 is a front elevational view of the sixth embodiment; and, FIG. 24 is a top view of the sixth embodiment. The broken lines in the drawings illustrate portions of the environment of the rising arch luminaire arm, which form no part of the claimed design.
